UNITED STATES PATENT OFFICE.

DAVID H. TAYLOR AND BENJAMIN E. CONNELLY, OF WHEELING, WEST VIRGINIA.

DRIVING MECHANISM.

1,109,088.

Specification of Letters Patent.

Patented Sept. 1, 1914.

Application filed March 3, 1913. Serial No. 751,862.

To all whom it may concern:

Be it known that we, DAVID H. TAYLOR and BENJAMIN E. CONNELLY, citizens of the United States, residing at Wheeling, in the 5 county of Ohio and State of West Virginia, have invented certain new and useful Improvements in Driving Mechanism, of which the following is a specification.

This invention relates to buffing, polishing, and grinding machines, and has for its 10 object the provision of a compact and simply arranged machine which may be readily controlled and guided by hand and which will operate economically and efficiently.

15 A further object of the invention is to provide a machine of simple form whereby a plurality of buffing wheels may be actuated simultaneously.

The several objects of the invention are 20 attained in such a mechanism as is illustrated in the accompanying drawings, and the invention consists in certain novel features which will be hereinafter first fully described and then more particularly pointed 25 ed out in the appended claims.

The annexed drawing shows a plan view partly broken away and in section of an apparatus embodying our present invention.

In carrying out our invention, we employ 30 a casing 1 in which is housed an electric motor, the cable 2 by which the motor is connected to a source of electric energy being extended through the rear end of the casing. The casing is preferably constructed in two duplicate members secured 35 together by screws or similar fastening devices 3 and provided with lateral offsets or wings 4 having slots 5 extending longitudinally thereof to constitute handles where- 40 by the casing may be grasped and directed over the surface to be treated. A driving shaft 6 extends through one end of the casing and is connected within the casing directly to the motor which may be of any pre- 45 fered or convenient type. The casing is provided with an extension 7 constituting a gear casing and within the said gear casing a beveled gear wheel, indicated at 8 in dotted lines, is fixed upon the driving shaft. 50 Stub-shafts 9 and 10 are journaled in the bearings 11 provided therefor on the sides of the gear casing, as clearly shown. Beveled gear wheels, indicated in dotted lines at 12,

are fitted on the inner ends of the stub-shafts and mesh with the bevel gear wheel 8, 55 as will be readily understood. Fixed upon the outer ends of the shafts 9 and 10 are buffing wheels 13 which, it will be seen at once, are caused to rotate in opposite directions through the described gearing. The 60 outer end of the driving shaft 6 is threaded, as shown at 14, and upon the said threaded end of the shaft is engaged the hub 15 of a buffing wheel 16.

It will be readily seen from the foregoing 65 description, taken in connection with the accompanying drawings, that we have provided a very simple and compactly arranged mechanism whereby a plurality of buffing wheels may be simultaneously operated so 70 that a large surface may be quickly polished. The wheel 16 will operate in a plane at right angles to the wheels 13 which move in parallel planes but in opposite directions so 75 that a very high polish may be imparted to the treated surface by successively moving the several buffing wheels over the same portion of the surface. The main casing or housing for the motor, being provided with a handle on each side, may be manipulated 80 without fatiguing the operator and the power is applied directly from the motor to the buffing wheels. The buffing wheel 16, it will be readily seen, is removable and a grinding wheel may be substituted therefor 85 when so desired. The device may also be utilized as a drilling machine by substituting for the buffing wheel 16 or the grinding wheel a drill chuck in which is held a drill bit, as will be readily understood. 90

The gear casing or extension has an open top which is normally covered by a hinged lid. The casing is filled with oil in which the bevel gears run so that thorough lubrication will be effected and the lid is constructed to fit tight against the casing to prevent loss of the lubricant. 95

What we claim is:—

1. The combination of a casing having lateral longitudinally extending offsets on 100 its sides provided with longitudinal slots, a gear casing carried by one end of said first-mentioned casing, a motor mounted in the first-mentioned casing, a shaft extending from said motor through the gear casing, 105 shafts journaled in the gear casing and pro-

jecting laterally therefrom, and gearing within said casing connecting said shafts.

2. The combination of a casing having lateral longitudinally extending offsets on its sides provided with longitudinal slots, a motor within the casing, a shaft extending from the motor and the casing, and gearing actuated by the outer end of said shaft.

In testimony whereof we affix our signatures in presence of two witnesses.

DAVID H. TAYLOR. [L. S.]
BENJAMIN E. CONNELLY. [L. S.]
